DESIGN FOR A PINKING MACHINE

William T. Maxant, Ayer, Mass.

Application October 30, 1934, Serial No. 53,825

Term of patent 7 years

To all whom it may concern:

Be it known that I, William T. Maxant, a citizen of the United States, residing at Ayer, in the county of Middlesex and State of Massachusetts, have invented a new, original, and ornamental Design for Pinking-Machines, of which the following is a specification, reference being had to the accompanying drawing, forming part thereof.

The figure is a perspective view of a pinking-machine, showing my new design from one side of the machine, the opposite side being of the same or substantially the same contour.

I claim:

The ornamental design for a pinking-machine, as shown and described.

WILLIAM T. MAXANT.
